FLY SWATTER

Frank H. Klie, Paris, Ill.

Application July 7, 1937, Serial No. 152,330

3 Claims. (Cl. 43—137)

The present invention relates to the structure of so called fly swatters and is particularly directed to improvements in the handle portion thereof.

5 The objects of the invention are to provide a light, well balanced, article having the degree of flexibility required for efficient use and a handle shaped to provide a comfortable grip. Other objects are to provide a construction which is inexpensive and which permits the swatters to be stacked for shipment in bulk without waste of space.

10 The foregoing objects are attained by forming the elongated handle of the swatter of strips of thin, flexible material, such as wood veneer, arranged in layers and connected in such a way as to permit relative movement between the strips longitudinally thereof as the handle bends during use of the swatter.

15 A preferred form of construction embodying the invention is specifically described below and illustrated in the accompanying drawing, where

20 Figure 1 is a plan view of a fly swatter embodying the invention;

25 Figure 2 is an edge view of the structure seen in Figure 1;

30 Figure 3 is a plan view of a fly swatter having certain modifications of the connecting means for the handle shown in Figure 1;

35 Figure 4 is an edge view of the upper portion of Figure 3;

40 Figure 5 is an enlarged sectional detail view on the line 5—5 of Figure 1; and,

45 Figure 6 is a detail sectional view on the line 6—6 of Figure 1.

The construction shown in Figures 1 and 2 comprises a blade or flap portion 10 formed from any suitable material such as rubber fabric or wire screening. The flap 10 is secured as by a

50 rivet 11 between the ends 12 of elongated resilient strips 13 which form the swatter handle. The strips 13 are preferably formed of thin wood veneer, which material has been found to possess the necessary resiliency and stiffness when used

55 in two or more layers to provide the necessary bend or yield in the handle most effective when using the swatter. In order to increase the resiliency of the handle while retaining its necessary strength and stiffness, the two strips employed are loosely connected at two widely spaced points on the handle. Preferably, one connecting element or rivet 14 is located at the upper end of the handle adjacent to its junction with the flap 10, and the other connecting rivet 15 is located near the end of the handle. These rivets 14 and 15

are received in oversized openings formed in the strips 13. This provides a free space around the body of the rivet, as best seen at 16 in Figures 5 and 6. With this construction the two strips 13 are allowed a limited amount of slippage or relative movement longitudinally when the handle is flexed or bent as the swatter is used. The movement thus made possible is illustrated in Figure 6 where the lower strip 13 is shown as displaced with respect to the adjacent strip to the extent 10 permitted by the free space 16.

Figures 3 and 4 illustrate a slightly modified type of connection between the handle strips. In these figures wire staples 17 and 18 are used in lieu of the rivets 14 and 15, above described. 15 The staples 17 and 18 are loosely secured in the strips and permit substantially the same movement as provided for with the rivet constructions before described. A third staple 19 secures the ends of the strips 13 to the flap or blade in the 20 same manner as the rivet 11 in the construction first described. The rivet 11 and the staple 19, used to secure the handle to the flap, are preferably firmly seated in the material as relative movement at that point is not necessary. Obviously, the handle could be connected to the flap in any other suitable manner. The handle strips are preferably of identical size and contour, as shown, and formed with an end grip or hand hold 25 shaped to conform to the palm of the user's 30 hand.

With either of the modifications of connecting means above described, the handle structure possesses both stiffness and resiliency, the resiliency being increased by the fact that the two 35 strips composing the handle are not rigidly connected but may have movement upon each other as the handle bends. With such structure a fly swatter is provided which is light and which has the necessary yield to give the most efficient action when swatting insects. Also, the flat, thin construction of the swatter permits a number of them to be piled in a minimum amount of space for shipment in wholesale lots.

40 What is claimed as new is:

45 1. A fly swatter comprising a flap and an elongated handle consisting of a plurality of thin strips of flexible fibrous material secured to the flap and lying in contact with each other throughout most of their lengths therebeyond, and metallic fastening means loosely engaged in the contacting portions of the strips and joining them at 50 two points only, one of which is adjacent the flap and the other near the free end of the handle, whereby the handle strips may slip longitudi- 55

nally upon each other during use, said strips terminating in enlarged portions forming a grip of a width and shape to fit the palm of a user's hand.

2. A fly swatter comprising a flap and an elongated handle consisting of a pair of strips of thin wood veneer secured to the flap and lying in contact with each other throughout most of their lengths therebeyond, and rivets connecting the strips adjacent the flap and at a point near the 10 end of the handle, said rivets being secured in one of the strips and engaged in an oversized opening in the other to permit relative movement

of the strips longitudinally during use of the swatter.

3. An elongated handle for fly swatters or the like consisting of a plurality of superimposed strips of wood veneer of similar contour adapted at one end for connection to a flap, fastening elements loosely connecting the strips at two longitudinally spaced points and retaining them in frictional contact, the other end of said strips being formed with a grip portion having its edges 10 shaped to fit a user's hand.
